 tion of Illinois

Application August 18, 1945, Serial No. 611,339

8 Claims. (Cl. 101—1)

1
 This invention relates to new and useful improvements in outer jackets for moistening and inking rollers of lithographic printing machines and also to apparatus for applying such jackets, in tubular form, to such rollers.

The general practice which has been extensively used in jacketing rollers of the character above referred to, consists in sewing around the roller a piece of relatively resilient, comparatively thick fabric material having liquid absorbent characteristics. One of the fabric materials which has been extensively used is termed "Molleton," the thickness of which is in excess of $\frac{1}{8}$ inch and which in general has been found very satisfactory for distributing liquid evenly and uniformly over the plate. The jacketing material is sewed around the roller along the longitudinal abutting marginal edges thereof, and each of the overhanging end portions of the material has a draw-cord stitched to the marginal edges thereof, by over-hand stitching, so that the cords may be drawn taut to form the overhanging portions of the jacket snugly around the end portions of the roller and in surrounding relation to the projecting shaft portions of the roller. The ends of the cords are then tied firmly together.

Such coverings are removed from the rollers, after they are soiled by ink and moistening fluid, by severing the stitching and scraping them off the roller. The matter of renewing outer jackets of such rollers is extremely time consuming, and it usually requires three to four hours to sew a fresh jacket or covering onto a roller of average length.

Rollers for lithographing machines generally range from 2 inches to $3\frac{3}{4}$ inches in diameter and from $10\frac{1}{2}$ inches to 79 inches in length. Such rollers usually include a central core or shaft of metal surrounded by a body of resilient material, such as rubber. The rubber body is usually covered by one or more intermediate layers of suitable resilient material such as flannel, knitted wool or cotton, and around which the outer covering or jacket of absorbent material is stitched.

I am aware of one proposed practice for effecting a saving of time in applying outer jacket coverings for such rollers and which is disclosed in the Morris Patent No. 1,760,370 dated May 27, 1930.

The Morris patent discloses an arrangement wherein the roller includes an enlarged body portion formed as an integral part of the metal core or shaft, and around which may be quickly and easily telescoped an assembly, in tubular form, composed of a fiber or paper tube around which

2
 are two coverings of resilient fabric and around which an outer jacket or covering is sewed. While the Morris patent does disclose an arrangement which effects a saving of time in the replacement of jackets on the rollers, approximately the same amount of time is required in stitching such jackets around the replaceable tubular assembly, prior to mounting the tubular jacket assembly on the roller. Hence, the time required in the Morris arrangement is not actually saved, but is transferred from the machine operator to a person making up the tubular assembly. Moreover, Morris' construction and arrangement is such that there will not be a firm anchorage of the outer covering with respect to the body of the roller, which is considered important for obtaining uniform distribution of the fluid over the plates. In the Morris arrangement the outer jacket is merely sewed longitudinally around the built up body composed of the fiber tubular core and two layers of intermediate covering. No arrangement is disclosed wherein the outer jacket is anchored at opposite ends so that the covering remains stretched tautly lengthwise of the roller to insure against the possibility of bulging or unevenness of surface contour. Furthermore, forming the body of the roller of metal, as proposed in the Morris patent, in order to conveniently accommodate the fiber tubular core of the jacket assembly, results in a loss of the advantage of having a resilient material constituting the main body of the roller.

A further disadvantage of the arrangement suggested in the Morris patent is that each time the outer jacket or cover is to be renewed it is necessary that the entire tubular covering assembly be discarded. This practice is extremely costly because in such renewal operation not only is there the attendant cost of replacing the outer liquid absorbing jacket material, but there is also the additional cost of two or more intermediate coverings of resilient material such as wool, as well as the cost of the paper or fiber core.

One of the objects of this invention is to provide an improved tubular outer jacket and novel apparatus for applying said jacket to rollers of lithographing machines in a manner so as to result in a saving of several hours' time as compared to present day conventional methods of producing and applying outer jackets to such rollers.

Another object is to provide a novel apparatus for applying a preformed tubular outer jacket to rollers of lithograph printing machines in a few minutes' time.

A further object is to provide novel apparatus for quickly and easily applying a preformed tubular outer jacket to a roller of a lithograph printing machine and wherein said apparatus may be quickly and easily adjusted for performing a jacketing operation on rollers of various lengths.

Still another object is to provide novel apparatus for mechanically jacketing a roller of a lithograph printing machine and wherein said apparatus is relatively simple in construction, durable and efficient in operation, and capable of being economically manufactured.

A still further object is to provide a novel, pre-formed tubular outer jacket for rollers of lithograph printing machines having means at one end thereof for quickly and easily constricting the end portion of the tubular jacket to form a transverse shoulder for snugly fitting against the end portion of the roller in surrounding relation to the metallic projecting end portions of the core or shaft of the roller.

Other objects and advantages of this invention will be apparent from the following description, taken in connection with the accompanying drawings, in which:

Figure 1 is a side elevational view of the novel apparatus and the novel form of tubular jacket embodying the present invention, with a roller shown positioned preparatory to insertion into the apparatus for performing a jacketing operation thereon;

Figure 2 is a view similar to Figure 1 and showing the roller and the apparatus in a position at which the roller has been telescoped within the tubular jacket;

Figure 3 is a face view of the apparatus;

Figure 4 is a horizontal sectional view through the apparatus taken substantially as indicated at line 4—4 on Figure 1;

Figure 5 is a transverse sectional view through the upper portion of the mandrel and supporting bracket, taken substantially as indicated at line 5—5 on Figure 4;

Figure 6 is an enlarged sectional view through the jack mechanism, taken substantially as indicated at line 6—6 on Figure 3;

Figure 7 is an enlarged face view of the upper portion of the apparatus, taken substantially as indicated at line 7—7 on Figure 2;

Figure 8 is an enlarged fragmentary view of one end portion of the tubular outer jacket embodying the present invention;

Figure 9 is a view in side elevation of a modified arrangement of the apparatus embodying the present invention; and

Figure 10 is a transverse sectional view through the modified apparatus, taken substantially as indicated at line 10—10 on Figure 9.

When it is necessary to renew soiled outer jackets of rollers of lithograph printing machines said outer jackets are cut off of the roller in a customary manner such as by means of a knife. The jacket 10, which is to constitute the outer cover for a roller, indicated at 11, is preformed as a tube, and when made up of materials such as "Molleton" the abutting marginal longitudinal edges thereof are stitched together, preferably on a sewing machine, as indicated at 10^a and the tubular jacket is internally dimensioned so as to insure a relatively snug fit on said roller 11.

The roller is of usual construction, including a central metallic core 12, surrounded by a body of resilient material 14, such as rubber, the latter being encased in one or more coverings 15, of suit-

able material, such as flannel and/or knitted wool or cotton. The projecting end portions 16, of the core of the roller are of suitable lengths for mounting in bearings of the machine.

The tubular jacket is of a length as to provide overhanging end portions when it surrounds the roller and at least one end portion as seen in Figure 3 of the drawings, is provided with a multiplicity of circumferentially spaced apart metallic eyelets 18, through which is threaded a suitable cord of drawstring 19. The eyelets serve to firmly grip the fabric between shoulders thereof and provide a strong, durable fastening on which substantial strain may be imposed without tearing the fabric. The eyelets may be provided in the end portion of the jacket either prior to the forming of the material as a tube, or after it is so formed. When the roller is to be re-covered with a new tubular outer jacket 10, desirably the draw string 19 is drawn together to form a transverse stop shoulder as indicated at 10^b in Figure 1 of the drawings, against which the end of the roller body is adapted to abut, as will hereinafter be described. By using the eyeletting and draw cord arrangement, I have found that it saves approximately one hour's time which would be required in sewing the end of the jacket in the manner heretofore practiced.

The apparatus for applying a new tubular outer jacket to the roller 11, as shown in the drawings, comprises a mounting base 21, to which is rigidly secured at the upper end thereof, a bracket 22. Removably mounted on the lower portion of the base 21, in alignment with the bracket 22, is a second bracket 23, having a horizontally extending shelf 24, and connecting side flanges 25, adapted to fit against the edges of the base 21. The rear edges of the flanges 25, are each provided with a pair of longitudinally spaced apart bayonet slots 27, adapted to cooperate with a pair of adjacent headed studs 29, of a series of studs projecting laterally from the edges of the base member 21. By virtue of this arrangement the bracket 23, may be adjusted vertically on the base member 21, so as to readily accommodate, between the brackets 22 and 23, rollers of various lengths.

Rigidly attached to the outer portion of the bracket 22, and extending downwardly in parallel relation to the base 21, is a guide bar 32, the end portion, opposite its fixed connection to the bracket 22, being mounted for sliding guidance and support in a bearing boss 33, formed on the outer end of the bracket 23. Said guide bar is of generally V-shaped cross section, and the trough portion of the V is provided with a multiplicity of longitudinally spaced apart teeth 35, with which cooperate alternately actuated, locking and feeding dogs 36 and 37 of a conventional jack mechanism indicated generally at 40. The dogs are normally yieldingly urged downward by a spring 40^a, controlled by a lever 40^b, having a spring abutment 40^c. When the spring pressure is released by movement of lever 40^b, the dog 37 may be raised by the finger piece 40^d so that the jack may be freely moved along the guide bar 32. The jack mechanism may be of any suitable form and as shown includes a hand operating lever 41, which is pivoted at 42 to the housing and pivoted at 36^a and 37^a to the dogs 36 and 37, so that upon reciprocation of the lever, the entire jack mechanism is caused to be fed forcibly along the guide bar 32. The jack mechanism includes a body portion 40^e mounted in sliding guidance with the under surface of the V-shaped guide bar 33 and is provided with a laterally projecting foot

43, formed with a socket member 44 for the reception of the upper end of one of the core projections 16, of the roller to be jacketed.

The horizontally extending shelf 24 of the second bracket 23 is formed with a relatively large central aperture 45 through which is adapted to be projected one of a number of different size and length mandrels, as indicated generally at 46. It is to be understood that for various diameters and lengths of rollers, a correspondingly dimensioned mandrel is employed.

The mandrel 46 comprises an elongated body of bifurcated form, leaving a pair of elongated resilient fingers 47, of circular contour in cross section. The fingers are formed as sheet metal stampings and have their upper ends bent to form transversely extending flanges 48, which flanges are firmly gripped between a pair of metallic rings 49 and 50, and rigidly connected in assembled relation by screws 51. The rings together with the flanges 48 thus constitute a head adapted to be supported upon the horizontal shelf 24, of the movable bracket 23, with the body portion 46 of the mandrel projecting through the aperture 45, as seen in Figure 5.

Because the apparatus is intended to accommodate mandrels of various diameters, the aperture 45 by necessity is of a size to accommodate the largest diameter mandrel to be utilized. In order that all of the mandrels to be used with the apparatus may be maintained in central alignment with the socket 44 on the arm 43 of the jack mechanism, the inner ring member 50 of the head of the mandrel is provided with a pair of diametrically opposite, depending pins 55 which are adapted to be seated in correspondingly aligned openings 56 formed in the shelf portion 24 of the bracket 23, as seen in Figures 4 and 5 of the drawings.

It is to be understood that the fingers 47 of the mandrel are formed of relatively thin sheet metal and are dimensioned transversely in proper co-relation to the diameter of the roller to be recovered. Preferably the internal diameter of the fingers of the mandrel is such that the roller 11 will be snugly engaged therewith as it is moved therethrough. Likewise the external transverse diameter of the fingers of the mandrel must be in co-relation to the internal diameter of the tubular jacket to be applied to the roller, and hence the internal diameter of the tubular jacket desirably is such as to provide a snug telescopic fit over the fingers of the mandrel preparatory to performance of the jacketing operation. When using "Molleton" material, I have obtained very satisfactory results when the jacket is formed with an internal diameter 1/16 inch less than outer diameter of the roller.

While I have shown in Figures 1 and 2 of the drawings the tubular sleeve completely telescoped over the fingers of the mandrel, it is to be understood that if a more snug fit is desired for the outer jacket around the roller the internal diameter of the jacket should be slightly reduced so that the jacket may be telescoped only over the major portion of the length of the mandrel, approximately in the range of one-half to three-quarters of the length thereof. The reduction in diameter of the jacket will be accommodated by the resiliency of the fingers 47 of the mandrel due to the particular formation thereof and their fixed mounting at one end.

When it is desired to re-cover a roller as indicated at 11, a preformed tubular outer jacket 10 is telescoped over the fingers 47 of the man-

drel as seen in Figure 1 of the drawings. As above indicated, the outer end of the tubular jacket is first constricted by drawing the draw-cord 19 tautly so as to form a transverse shoulder, 10^b, as clearly seen in Figure 1 of the drawings.

The roller 11 is then dropped partially through the mandrel from the position seen in Figure 1 of the drawings, but due to the internal dimensions of the mandrel, in order to obtain a relatively snug fit of the jacket around the roller, said roller must be forcibly moved downwardly through the mandrel. The jack mechanism is then operated so as to first fit the socket portion 44 around the upper end of the core projection 16 of the roller, and the jack mechanism is then further operated along the guide bar 33 by manipulation of the lever 41, which thereby forcibly moves the roller 11 downwardly through the mandrel, as seen in Figure 2 of the drawings. As the roller passes through the mandrel the lower transverse face or end of the roller abuts against the shoulder 10^b formed by constricting the lower end of the jacket. When the roller has been moved into the mandrel to a position at which the lower end of the body of the roller engages the shoulder formed by the constriction of the tubular jacket, the jack mechanism is released and moved upwardly so as to permit the insertion of a bar or tubular member, as indicated at 60, in dotted outline in Figure 2 of the drawings, with the lower end of the tube abutting the upper end of the core projection 16 of the roller and with the upper end of the tube seated in the socket 44 of the arm 43 of the jack mechanism, whereby further operation of the jack mechanism, through the medium of the tubular member 60, causes the roller 11 to be moved downwardly through the mandrel, thereby stripping the tubular jacket 10 off of the fingers of the mandrel and causing it to be deposited in snug embracing relation around the roller as above referred to. The opposite end of the jacket is then constricted and formed to fit around the other end of the roller by a draw cord as above described, or may be sewed in proper place and formed in a usual manner.

Figures 9 and 10 disclose the apparatus mounted in horizontal relation and which is desirable particularly when the rollers to be jacketed are of relatively great length. In this arrangement of the apparatus the various parts thereof are identical with the parts of the apparatus disclosed in Figures 1 to 7, inclusive, of the drawings, and as above described, and in addition there is provided an auxiliary roller 70 disposed with its axis in a horizontal plane and journaled at its opposite ends in brackets 71, secured to the edges of the base member 21. Said roller and brackets are positioned forwardly of the innermost pair of studs 29, and the central portion thereof is recessed as indicated at 74, to form a trough and provide proper guidance and support for the forward end of the roller 11, preparatory to its being fed into the mandrel 46, for the performance of the jacketing operation. The apparatus in this horizontal arrangement is operated in the same manner as that above described.

While I have herein referred to "Molleton" as the material for providing outer jackets for the rollers, manifestly other materials may be satisfactorily employed, and may be made up as endless tubing cut to desired lengths. In such cases, the eyeletting operation may still be satisfactorily employed with the attendant advantages above indicated.

Although I have herein shown and described certain preferred embodiments of my invention, manifestly it is capable of modification and rearrangement of parts without departing from the spirit and scope thereof. I do not, therefore, wish to be understood as limiting this invention to the precise forms herein disclosed, except as I may be so limited by the appended claims.

I claim as my invention:

1. Apparatus for mechanically jacketing a roller of a lithograph printing machine with a tubular sleeve of absorbent fabric, comprising a hollow mandrel dimensioned internally for snugly receiving telescopically a roller to be jacketed, and dimensioned externally for a snug fit thereon of the major portion of the length of a tubular sleeve of absorbent fabric, means for supporting the mandrel, and means for forcibly moving the roller through the mandrel and stripping the sleeve off the mandrel and simultaneously causing the sleeve to embrace and surround the roller.

2. Apparatus for mechanically jacketing a roller of a lithograph printing machine with a tubular sleeve of absorbent fabric, comprising a hollow, split mandrel dimensioned internally for snugly receiving telescopically a roller to be jacketed, and dimensioned externally for a snug fit thereon of the major portion of the length of a tubular sleeve of absorbent fabric, means for supporting the mandrel totally at one end, and means for forcibly moving the roller through the mandrel and stripping the sleeve off the mandrel and simultaneously causing the sleeve to embrace and surround the roller.

3. In combination, a hollow mandrel having a supporting head and a longitudinally split body providing two yieldable elongated fingers, said mandrel being internally dimensioned for snugly receiving telescopically a roller to be jacketed, and dimensioned externally for a snug telescopic fit thereon of the major portion of the length of a tubular sleeve of absorbent fabric, means cooperating with said head for totally supporting said mandrel, and means for forcibly moving a roller through the supported end of the mandrel and causing the sleeve to be stripped off the mandrel and deposited in a snug embracing relation on said roller.

4. In combination, a hollow mandrel having a supporting head and a bifurcated, longitudinally extending body, said mandrel being internally dimensioned for snugly receiving telescopically a roller to be jacketed, and dimensioned externally for a snug telescopic fit thereon of the major portion of the length of a tubular sleeve of absorbent fabric, means cooperating with said head for totally supporting said mandrel, and means adapted to engage one end of the roller for forcibly moving it through the supported end of the mandrel and causing the sleeve to be stripped off the mandrel and deposited in a snug embracing relation on said roller.

5. In combination with a roller of a lithograph printing machine and a tubular sleeve of absorbent fabric; a base, a stationary bracket mounted on the base, a second bracket mounted on the base, said brackets being aligned and spaced apart to freely accommodate said roller lengthwise therebetween, a fixed guide bar interconnecting said brackets, a hollow mandrel having a head and an elongated resilient body mounted on and totally supported at one end by said head on said second bracket, said mandrel being internally dimensioned for a snug telescopic fit with said roller to be jacketed, and ex-

ternally dimensioned for a snug telescopic fit thereon of the major portion of the length of said tubular sleeve of absorbent fabric, and means mounted on and movable along the guide bar, and having a member for engaging one end of said roller for forcibly moving it through the mandrel and thereby stripping the sleeve off the mandrel and depositing it in a snug embracing relation on said roller.

6. In combination with a roller of a lithograph printing machine and a tubular sleeve of absorbent fabric; a base, a stationary bracket mounted on the base, a second bracket mounted on the base, said second bracket and base having cooperating features for releasably anchoring said bracket to the base at a plurality of positions of adjustment toward and away from the stationary bracket for freely accommodating a roller of predetermined length therebetween, a fixed guide bar interconnecting said brackets, a hollow mandrel having a head and an elongated resilient body removably mounted on and totally supported at one end by said head on said second bracket, said mandrel being internally dimensioned for a snug telescopic fit with said roller to be jacketed, and externally dimensioned for a snug telescopic fit thereon of the major portion of the length of said tubular sleeve of absorbent fabric, and means mounted on and movable along the guide bar, and having a member for engaging one end of said roller for forcibly moving it through the mandrel and thereby stripping the sleeve off the mandrel and depositing it in a snug embracing relation on said roller.

7. In combination with a roller of a lithograph printing machine and a tubular sleeve of absorbent fabric; a base, a stationary bracket mounted on the base, a second bracket mounted on the base, said brackets being aligned and spaced apart to freely accommodate said roller lengthwise therebetween, a fixed guide bar interconnecting said brackets, a hollow mandrel having a head and an elongated resilient body mounted on and totally supported at one end by said head on said second bracket, said mandrel being internally dimensioned for a snug telescopic fit with said roller to be jacketed, and externally dimensioned for a snug telescopic fit thereon of the major portion of the length of said tubular sleeve of absorbent fabric, and means mounted on and movable along the guide bar, and having a member for engaging one end of said roller for forcibly moving it through the mandrel, the free unsupported end of said sleeve being restricted to form an abutment shoulder adapted to be engaged by the leading end of the roller as it moves through the mandrel, whereby said sleeve is caused to be stripped off the mandrel and deposited in snug embracing relation on said roller.

8. In combination with a roller of a lithograph printing machine and a tubular sleeve of absorbent fabric; a base, a stationary bracket mounted on the base, a second bracket mounted on the base in aligned, spaced apart relation to the first bracket, a fixed guide bar interconnecting said brackets, a mandrel having a head and an elongated hollow resilient body connected to said head at one end, said mandrel being removably mounted on said second bracket with said body extending through an aperture in the bracket, and the head and bracket having interengaging features for releasably connecting said head to the bracket for supporting the body in central relation to the aperture, said mandrel being internally

dimensioned for a snug telescopic fit with said roller, and externally dimensioned for a snug telescopic fit thereon of the major portion of the length of said tubular sleeve, and means mounted on and movable along the guide bar and having a member for engaging one end of said roller for forcibly moving said roller through the mandrel and thereby stripping the sleeve off the mandrel and depositing it in a snug embracing relation on said roller.
